UNITED STATES PATENT OFFICE.

ALFRED SCHULTE, OF VELBERT, GERMANY.

LOCK.

Application filed May 14, 1921. Serial No. 469,709.

(GRANTED UNDER THE PROVISIONS OF THE ACT OF MARCH 3, 1921, 41 STAT. L., 1313.)

To all whom it may concern:

Be it known that I, ALFRED SCHULTE, a citizen of Germany, residing at Velbert, Rhenish Prussia, Germany, have invented 5 certain new and useful Improvements in Locks (for which I have filed applications for patent in Germany, June 23, 1919; Netherlands, June 12, 1920; England, June 30, 1920,) and of which the following is a 10 specification.

My invention relates to a latch-lock the latch-bolt of which serves simultaneously as a lock-bolt the same being capable of being advanced beyond its latching position into 15 a locking position. The main object of my invention is to raise the safety of a lock of this kind by the combination with it of two cylinder- or barrel-locks with tumbler- and setting-pins, and of a special tumbler for 20 the latch-bolt in such a manner that the latch-bolt can be advanced from its latching position into its locking position and vice versa only by means of the cylinder-locks which are operable each from one side 25 of the door, whereas its retraction from the latching position into the lock-casing may be effected by the cylinder-locks as well as by a handle arranged at the inner side of the door. By this combination an absolute 30 safety against unauthorized opening from both sides of the door is afforded while the lock itself is very simple in construction.

To more simplify my combined lock I arrange the two cylinder-locks in staggered 35 relation and provide each with a separate driving member for the latch-bolt. Thus complicated and unreliable means for coupling a common driving member alternately with either of the two cylinder-locks are 40 avoided. Furthermore by this arrangement it is possible to position one of the cylinder-locks wholly or partly within the casing of the latch-lock.

One embodiment of the invention is shown 45 by way of example in the annexed drawing, wherein:

Fig. 1 shows the lock with the cover removed and with the latch-bolt withdrawn into the casing,

50 Fig. 2 shows the lock with the latch-bolt in its latching position,

Fig. 3 is a transverse section on the line A—B in Fig. 2,

55 Fig. 4 is a longitudinal section on the line C—D in Fig. 2,

Fig. 5 is a transverse section on the line E—F in Fig. 2, and

Fig. 6 is a view similar to Fig. 1 but with the latch-bolt advanced to its locking position.

The box-like casing *a* of the lock comprises the flange *b* and a plate *c* fastened on the bottom of the casing *a* which is closed by means of the cover *d* held at the proper distance from the bottom by means of suitable 65 bolts not shown on the drawing. *e* is the latch-bolt which serves simultaneously as a lock-bolt and which at its head formed by bending up side flaps is guided in the flange *b* and at its longitudinal edges is guided in the turned up walls of the casing *a*, said latch-bolt at its rear end sliding on the bottom of the lock by means of a flap *f* bent up at right angles. A spring *g* acting on 70 the rear end of the latch-bolt *e* tends to hold 75 the same in its latching position, that is to press it always forward into this position. The latch-bolt however is capable of being advanced beyond its latching position into a locking position wherein it abuts against 80 the flange *b* of the casing. To limit the forward movement of the latch-bolt at the latching position and to secure it in the advanced or locking position, a tumbler *i* pivoted at one end on a stationary pin *h* is provided which tumbler has a spring *k* pressing against the upper wall of the casing and at its other end and on its lower edge has two lugs *l* and *m* one of which engages between two upwardly converging stops *n*, *o* 85 mounted on the bolt *e*. The tumbler lug *l* which secures the latch-bolt in its locking position (Fig. 6) is so formed that in co-acting with the stops *n*, *o* it prevents motion of the bolt *e* in both directions, while the 90 second tumbler lug *m* has such a form that it prevents movement of the latch-bolt past its latching position (Fig. 2) but allows the latch-bolt to be withdrawn into the casing *a* 95 (Fig. 1), the stop *n* on the bolt *e* owing to the tumbler lug *m* being bevelled on one side being capable of lifting the tumbler on re-tracting the latch-bolt.

The latch-bolt *e* is moved first of all by means of two cylinder-locks *p*, *q* which are 105 arranged one behind the other in the direction of the bolt movement and of which one, *p*, can be operated from inside and the other, *q*, from outside the door. The former one, *p*, which is situated the nearer 110

to the front end of the lock extends into the casing *a* through a hole in the bottom of the latter and is fastened by being screwed at *r* on to the bottom of the lock 5 casing *a* or on to the lock plate *c*. The latch-bolt *e* has a suitable gap *e*¹ in which moves a key-bit-like driving pawl *s* fastened to and rotatable with the inner or rotary cylinder of the cylinder-lock *p*, and 10 in the upper portion of said gap *e*¹ are formed slots *t*, *u* which co-operate with said pawl so that when the pawl *s* is turned by means of the cylinder-lock *p* the tumbler *i* is first of all released and then the latch 15 is shot forward to its locking position or from this back to its latching position or finally retracted into the lock casing *a*.

The second cylinder-lock *q* which is arranged farther back, that is, is offset with 20 respect to the first one *p*, is inserted from the outside of the door into a hole in the same and is held in place, for example, by being screwed to the lock cover *d*. The inner or rotary cylinder of this second cylinder-lock *q* is also coupled to a key-bit-like driving pawl *v* which is rotatably mounted in the lock cover *d*, the two stops 25 *n*, *o* on the latch-bolt *e* serving as bolt-stops engaging said second driving pawl *v* so that, when the latter is turned by means 30 of the cylinder-lock *q*, the latch-bolt, after releasing of the tumbler *i*, can also be advanced from its latching position to the locking position and vice versa and finally 35 withdrawn into the lock casing.

In the bottom of the lock casing *a* there is turnably mounted a handle or knob *w* with which is connected a driving pawl or lever *x* acting on the flap *f* of the latch- 40 bolt *e* only. By turning the knob *w* the latch-bolt may be withdrawn from its latching position into the lock-casing, but owing to the driving pawl *x* being unable to act upon the tumbler *i* it is quite impossible to 45 retract the bolt *e* from its locking position by means of the handle *w*.

Claims:

1. In a latch-lock, in combination: a latch-bolt adapted to act simultaneously as 50 a lock-bolt and capable of being advanced beyond its latching position into a locking position, tumblers adapted to limit the forward movement of the latch-bolt at its latching position and also to secure the 55 latch-bolt in its locking position, two cylinder-locks operable from opposite sides of the latch-lock, driving members adapted to be coupled with said cylinder-locks and to co-act with said tumblers for releasing 60 them and simultaneously with said latch-bolt for advancing same from its latching position to its locking position and vice versa and for retracting the latch-bolt into the lock-casing also, a handle, and a driver 65 coupled with said handle and adapted to

act upon said latch-bolt only for retracting same from its latching position.

2. In a latch-lock, in combination: a latch-bolt capable of being advanced beyond its latching position into a locking position, 70 tumblers adapted to limit the forward movement of the latch-bolt at its latching position and also to secure said latch-bolt in its locking position, two cylinder-locks operable from opposite sides of said latch-lock, 75 said cylinder-locks being arranged in staggered relation, two driving members one each coupled with one of said two cylinder-locks and adapted to co-act with said tumblers for releasing same and simultaneously with said latch-bolt for moving the latter to its various positions, a handle, 80 and a driving member coupled with said handle and adapted to act upon said latch-bolt only for retracting same from its latching position. 85

3. In a door-lock, in combination: a latch-bolt capable of being advanced beyond its latching position into a locking position, 90 said latch-bolt being provided with two stops, a tumbler provided with two lugs and adapted to co-act with said stops for limiting the forward movement of said latch-bolt at its latching position and also for securing said latch-bolt in its locking position, 95 the rear one of said two tumbler lugs being bevelled on one side for automatically releasing said tumbler on retracting said latch-bolt from its latching position, two cylinder-locks operable from opposite sides of the latch-lock, 100 two driving members coupled with said cylinder-locks and adapted to co-act with said tumbler for releasing same and simultaneously with said latch-bolt for advancing same from its latching position to 105 its locking position and vice versa and for retracting the said latch-bolt into the lock casing also, a handle, and a driver coupled with said handle and adapted to act upon said latch-bolt only for retracting same from 110 its latching position.

4. In a latch-lock, in combination: a latch-bolt capable of being advanced beyond its latching position into a locking position, 115 said latch-bolt being provided with two stops consisting of two upwardly converging projections, a tumbler provided with two lugs and adapted to co-act with said stops for limiting the forward movement of said latch-bolt at its latching position and also 120 for securing the latch-bolt in its locking position, the rear one of said two lugs being bevelled on one side for automatically releasing said tumbler on retracting said latch-bolt from its latching position, two cylinder-locks operable from opposite sides of the latch-lock, 125 said cylinder-locks being arranged in staggered relation, two driving members one each coupled with one of said cylinder locks and adapted to release said 130

- tumbler and simultaneously to move said latch-bolt to its various positions, the driving member coupled with the forward one of said two cylinder-locks being situated in a recess of said latch-bolt, the upper edge of said recess forming notches for the engagement of said driving member, the driving member coupled with the rear one of said two cylinder-locks being situated in the plane of said two bolt-stops and adapted to engage same in driving the latch-bolt, a handle, and a driving member coupled with said handle and adapted to act upon said latch-bolt only for retracting same from its latching position.
5. In a latch-lock, in combination: a latch-bolt capable of being advanced beyond its latching position into a locking position, a tumbler adapted to limit the forward movement of said latch-bolt at its latching position and also to secure said latch-bolt in its locking position, two cylinder-locks fastened to the walls of the latch-lock casing and operable from opposite sides of the latch-lock, key-bit-like driving pawls coupled with the rotary cylinders of said two cylinder-locks and adapted to co-act with said tumbler for releasing same and simultaneously with said latch-bolt for moving same to its various positions, and a handle on one side of the latch-lock, and a lever-arm coupled with said handle and adapted to act upon said latch-bolt only for retracting same from its latching position.
- 30 6. In a latch-lock, in combination: a latch-bolt capable of being advanced beyond its latching position into a locking position, a tumbler adapted to limit the forward movement of said latch-bolt at its latching position and also to secure said latch-bolt in its locking position, two cylinder-locks fastened one to the bottom and the other to the cover of the latch-lock casing, and operable from opposite sides of the latch-lock, said two cylinder-locks being arranged in staggered relation, one of said cylinder-locks extending into the casing of said door lock, driving members coupled with said cylinder-locks and adapted to co-act with said tumbler for releasing same and simultaneously with said latch-bolt for moving same to its various positions, a handle arranged on one side of said latch-lock, and a driving member coupled with said handle and adapted to act upon said latch-bolt only for retracting same from its latching position.
- 35 7. In a door-lock, in combination: a latch-bolt capable of being advanced beyond its latching position into a locking position, said latch-bolt being provided with two stops, consisting of two upwardly converging projections, a tumbler provided with two lugs and adapted to co-act with said two stops for limiting the forward movement of said latch-bolt at its latching position and also for securing the latch-bolt in its locking position, the rear one of said two lugs being bevelled at its forward edge, two cylinder-locks operable from opposite sides of the latch-lock, said two cylinder-locks being arranged in staggered relation, the forward one of said cylinder-locks extending into the casing of the latch-lock, a key-bit-like driving pawl fastened directly to the rotary cylinder of said forward cylinder-lock, said driving pawl being situated in a recess of said latch-bolt, the upper edge of said recess forming notches for the engagement of said driving pawl, a second key-bit-like driving pawl rotatably mounted in the cover of the latch-lock casing and coupled with the rotary cylinder of the rear one of said two cylinder-locks, said second driving pawl being situated in the plane of said two bolt-stops and adapted to engage same in driving the said latch-bolt, both said driving pawls being adapted to release said tumbler and to move said latch-bolt to its various positions, a handle arranged on one side of the latch-lock, and a driving lever coupled with said handle and adapted to act upon said latch-bolt only for retracting same from its latching position.

In testimony whereof I affix my signature.

A. SCHULTE.
